LIPSTICK HOLDER OR THE LIKE

Simon Morrison, New York, N. Y.

Application July 26, 1935, Serial No. 33,283

8 Claims. (Cl. 206—56)

This invention relates to holders which are used to carry material in stick form or stick-like articles, and project the material or article from the holder for use. At present such holders are 5 most widely used for carrying lipstick, and hence the invention may be conveniently referred to as a lipstick holder or the like, it being understood that the holder may be used for other materials or articles.

10 The present invention particularly relates to lipstick holders of the type often referred to in the trade as "rotary" holders or "swivel" holders. These names connote the relative rotation which is imparted to two parts of the holder to effect 15 projection of the lipstick from the holder and its retraction into the holder. This type of holder is well known and widely used; and the present invention contemplates various structural innovations which improve the holder from the stand- 20 point of manufacture, assembly, and use.

Among the objects of the invention are to improve the construction of so-called rotary or 25 swivel holders from the standpoint of ease and expense of manufacture, small number of defective parts which are unsuitable for assembly, ease and speed of assembly, and reduction of difficulty due to jamming and wearing of parts when the holder is in use.

Fig. I is an elevation of a complete lipstick 30 holder embodying the present invention.

Fig. II is an elevation of the holder with the closure cap removed and the lipstick projected.

Fig. III is a vertical section of the holder in the condition shown in Fig. I.

35 Fig. IV is a horizontal section taken on line 4—4 of Fig. I.

Fig. V is an elevation corresponding to Fig. I but with certain exterior parts removed.

Fig. VI is an elevation with certain parts broken 40 away to show the interior construction and arrangement.

Fig. VII is a detail view, mostly in vertical section but partly in elevation showing, how the operating head is assembled onto the guide tube.

45 Fig. VIII is a detail vertical section showing the operating head permanently affixed to the guide tube.

In the original bristol-board drawing filed in 50 the Patent Office, of which the drawings hereto are reproductions on a reduced scale, Figs. I, II, and V are full size illustrations of a commercial embodiment of the invention. Figs. III and VI are double size illustrations, and Figs. IV, VII and VIII are four times enlarged.

55 As usual with rotary or swivel holders, the lip-

stick is projected from and retracted into the casing by effecting relative rotation between the exterior casing of the holder and the operating head at the end of the casing. Of course, the net result is the same whether the casing be held stationary and the head rotated (in one direction) or if the head be held stationary and the casing rotated (in the opposite direction). However, it is easier to read the drawings and understand the operation if it be considered that the head is held stationary and that the casing is rotated. Accordingly, the description throughout will be made as though the device were operated by holding the head stationary and rotating the exterior casing.

The lipstick 1 is telescopically mounted in a cup-shaped carrier 2, that is slidably telescoped within a guide tube 4, to which is fixedly attached an operating head 5. The guide tube 4 is provided with a vertical slot 6; and an operating pin 7 projects from the carrier 2 through the slot 6. The pin 7 may be suitably secured to the carrier 2 by friction, solder, or other means, but if arranged as shown in Fig. IV no special fixation is required. Preferably the pin has a head 7^a which is received in a recess or eyelet 2^a drawn from the metal of carrier 2; and the tip of the pin may be positioned in a similar eyelet 2^b. Embracing the guide tube 4 is a propelling sleeve 8, having a helical slot 9 into which the pin 7 also 30 projects. Independent of the helical slotting 9, which does not run quite the full length of the propelling sleeve 8, there is vertical end-to-end slotting of the propelling sleeve 8 by slot 10. It will be apparent that this sleeve 8 may be made 35 by diagonally slotting a rectangular piece of sheet metal and then rolling it into the sleeve 8. The diagonal slot then becomes the helical slot 9 and the metal is so dimensioned that when it is rolled into the sleeve the edges do not meet, but leave 40 the vertical end-to-end slot 10. Embracing the propelling sleeve 8 there is an exterior casing 12, provided with an indentation 13. In assembling the holder, the indentation 13 is inserted into the vertical slot 10 of the propelling sleeve, thus relatively locking together the casing 12 and the propelling sleeve 8. At its upper end, the casing 12 is provided with an inturned flange 12^a, which engages the top of the propelling sleeve 8 and thus prevents longitudinal movement of the propelling sleeve in one direction. By means of a swivel connection, which will be described presently, exterior casing 12 is allowed to rotate with respect to operating head 5. When casing 12 is so rotated, helical slot 9 acts on pin 7 to cam the 55

lipstick carrier 2 up and down in the guide tube.

The guide tube 4 may be made from a sheet metal tube, the lower end of the tube being flared outwardly to form a downwardly inclined flange 4^a. This flange 4^a may be a continuous plain flange, but in the alternative it is preferably serrated, as shown in elevation in Fig. VII. Operating head 5 is cup-shaped, and near the bottom of the cup an annular under-cut seat 5^a is formed on the inner side wall of the cup formation. Above the seat 5^a there is an annular bearing 5^b, and above that the inner wall of the cup is annularly recessed at 5^c. This leaves an inwardly extending bead 5^d at the top of the cup. The flange 4^a is of such a size that it initially telescopes snugly into the space embraced by seat 5^a. After being so telescoped, force is applied to the tube 4 in an axial direction, thereby bending the flange 4^a from its downwardly inclined angle to a horizontal position and causing the edge of the flange to enter into permanent locking engagement with the seat 5^a. It will be apparent that by serrating the flange 4^a, as shown in elevation in Fig. 7, the tolerance of parts may be increased and the locking action enhanced.

The lower end of the exterior casing 12 is enlarged slightly to form an annular bead 12^b; and several vertical slots 12^c are provided to form the lower portion of the casing into a series of 30 springy portions or fingers. It will be seen from Fig. VIII that the operating head 5 provides a cylindrical wall which is concentric with but spaced from the tube 4; and the exterior casing 12 is assembled onto the holder by simply forcing 35 it into the space between the head 5 and the tube 4. As the bead 12^b passes the bead 5^d the spring fingers yield inwardly; and then as the exterior casing is forced home, the spring fingers move outwardly, causing the bead 12^b to rest in 40 the annular recess 5^c. Thus the casing 12 is swivelly connected to the head 5, and is operatively held against axial movement in both directions. The lower end of the propelling sleeve 8 rests in bearing 5^b; and since the upper end of 45 the propelling sleeve is engaged by flange 12^a of the exterior metal casing 12, the propelling sleeve is also held against axial movement in both directions.

A short metal sleeve or thimble 15 is preferably 50 telescoped over the exterior casing 12 to cover the slots 12^c and provide an abutment against which the usual telescopic metal closure cap 16 may rest. Of course, the telescopic cap 16 makes a tight enough frictional fit so that it will not 55 fall off, but the fit is loose enough so that it can be removed readily. The sleeve 15 may make the same sort of a fit as the cap 16, or it may be a tight fit which renders it not readily removable. In the alternative, the sleeve 15 may be suitably 60 secured in place by solder or otherwise.

With respect to manufacture, the present construction involves considerable simplification as compared to prior art practice. The assembly is exceedingly simple, as it may be accomplished 65 by inserting the propelling sleeve 8 almost wholly within the exterior casing 12, then starting to telescope the parts together and engaging pin 7 in the lower end of the slot 9 and then forcing the casing 12 home so that the casing is placed 70 full length over the propelling sleeve 8 and is projected into swivel engagement with the head 5. In many of the previous lipstick holders friction had been relied upon to attach the propelling sleeve to the exterior casing and this required some springiness in the propelling sleeve 75

8 and was not a positive attachment, which sometimes resulted in jamming of the parts and failure to operate. With the present construction, however, the indentation 13 in the exterior casing effects a positive locking of the exterior casing to the propelling sleeve as far as rotation of the parts is concerned. ⁵

In compliance with the patent statutes, I have illustrated the best form in which I have contemplated applying my invention, and it will be realized that various modifications are possible and indicated within the scope of the appended claims.

What I claim is:

1. In a holder of the type in which a carrier is reciprocated in a slotted guide tube by relative rotation of a propelling sleeve which embraces the guide tube and is itself embraced by an exterior casing, the guide tube being open at one end and being provided at the other end with an operating head which is inseparable from the guide tube: the improvement which comprises a swivel connection between the operating head and one end of the exterior casing, said connection being effective to hold the exterior casing against longitudinal movement in both directions; an annular bearing formed in the head for one end of the propelling sleeve; and retaining means projecting inwardly from the other end of the exterior casing, said retaining means being effective to hold the propelling sleeve against longitudinal movement away from said bearing. ²⁵

2. In a holder of the type in which a carrier is reciprocated in a slotted guide tube by relative rotation of a propelling sleeve which embraces the guide tube and is itself embraced by an exterior casing, the guide tube being open at one end and being provided at the other end with an operating head: the improvement which comprises a swivel connection between the operating head and one end of the exterior casing, said connection being effective to hold the exterior casing against longitudinal movement in both directions; retaining means projecting inwardly from the other end of the exterior casing, said retaining means being effective to hold the propelling sleeve against longitudinal movement in one direction; and positive means to hold the exterior casing and the propelling sleeve in substantially fixed angular relation relative to each other. ⁴⁰

3. In a holder of the type in which a carrier is reciprocated in a slotted guide tube by relative rotation of a slotted propelling sleeve which embraces the guide tube and is itself embraced by an exterior casing: the improvement which comprises end-to-end severance of the propelling sleeve in such manner as to provide spaced apart edges, such severance being independent of the slotting of sleeve for propelling purposes; and an instruck projection on the exterior casing, said projection being positioned between the spaced apart edges of the propelling sleeve and thereby securing it in substantially fixed angular relation relative to the exterior casing. ⁵⁵

4. In a holder of the type in which a carrier is reciprocated in a slotted guide tube by relative rotation of a propelling sleeve which embraces the guide tube and is itself embraced by an exterior casing, the guide tube being open at one end and being provided at the other end with an operating head which is inseparable from the guide tube: the improvement which comprises a snap-together swivel connection between the op- ⁷⁰ 75

- erating head and one end of the exterior casing, said connection being effective to hold the exterior casing against longitudinal movement in both directions; an annular bearing formed in the head for one end of the propelling sleeve; and an in-turned flange on the other end of the exterior casing, said flange being effective to hold the propelling sleeve against longitudinal movement away from said bearing.
- 5 5. In a holder of the type in which a carrier is reciprocated in a slotted guide tube by relative rotation of a propelling sleeve which embraces the guide tube and is itself embraced by an exterior casing, the guide tube being open at one end and being provided at the other end with an operating head: the improvement which comprises the operating head having a flange which surrounds the guide tube in spaced relation therewith, and the propelling sleeve and the exterior casing being telescoped into the annular space between said flange and the guide tube, said flange making swivel connection with the exterior casing and being detachably secured thereto as against axial movement.
- 10 6. In a holder of the type in which a carrier is reciprocated in a guide tube in response to relative rotation imparted to an exterior casing which surrounds the guide tube, there being an operating head inseparably attached to the guide tube: the improvement which comprises the op-
- 15
- 20
- 25
- 30

erating head having an interiorly recessed annular flange, the flange surrounding the guide tube in spaced relation therewith; and the exterior casing having on its end, spring fingers in holding engagement with the recess of said annular flange.

7. In a holder of the type in which a carrier is reciprocated in a guide tube in response to relative rotation imparted to an exterior casing which surrounds the guide tube, there being an operating head attached to the guide tube: the improvement which comprises the operating head having an interiorly recessed annular flange, the flange surrounding the guide tube in spaced relation therewith; the exterior casing having on its end, spring fingers in holding engagement with the recess of said annular flange; and a sleeve telescoped over said exterior casing, said sleeve abutting against the edge of said flange and forming an abutment for a removable closure cap.

10 15 20 25 30 8. In a holder for stick material: a cup-shaped operating head having an annular seat adjacent to the bottom of the cup and an annular recess above said seat, a guide tube having a flange telescoped within the cup and deformed into permanent locking engagement with said seat, and a casing having a portion in swivel engagement with said recess.
